UNITED STATES PATENT OFFICE.

ALFRED AUSTIN WHITLEY, OF PRESTWICH PARK SOUTH, NEAR MANCHESTER,
ENGLAND.

CLIP FOR STENTERING MACHINES.

Application filed March 15, 1923. Serial No. 625,386.

To all whom it may concern:

Be it known that I, ALFRED AUSTIN WHITLEY, a subject of the King of Great Britain, residing at Clifton View, Prestwich Park South, near Manchester, in the county of Lancaster, England, have invented new and useful Improvements in Clips for Stentering Machines, of which the following is a specification.

10 My invention relates to stentering machine clips such, for instance, as are described and claimed in the specification of United States Letters Patent No. 1,050,755, granted to me. I refer more especially to 15 clips of the character shewn in, and described with reference to, Figures 10, 11, and 12 of the said specification.

The principal objects of my present invention are to improve clips of the kind referred to so as to allow of the opening of the upper jaw, without obstruction, as far as required to enable the cloth to be conveniently fed to the clips and the clips to be cleaned with facility, and generally to 25 provide a very convenient arrangement of the parts of the clips which will give efficient action thereof, and which, whilst preventing undue pressure of the gauge-tongues on the cloth, will provide efficient pressure 30 of the upper jaw to give a proper grip thereof upon the cloth.

According to my invention I arrange one 35 of the arms constituting the lever of the gauge-tongues, by which the said lever is centered to the upper jaw, outward of one of the arms by which the said jaw is connected, with its axis so that I can, when so desired, employ but one vertical arm on the body part of the clip. I also provide 40 for the lever of the gauge-tongues, an abutment, upon the said vertical arm, or upright, the said abutment causing the said gauge-tongues to be lifted when the upper jaw is opened. I also hinge a cam-piece 45 to the upper jaw and provide a spring which puts pressure on the upper jaw, to press the said cam-piece against an abutment carried by the vertical arm, the said parts being so arranged that the pressure which is 50 exerted upon the upper jaw by the spring

does not exert objectionable pressure upon the gauge-tongues when they rest upon the fabric.

I may provide a projecting snug at the upper part of the vertical arm to take a bearing against a plate, or the equivalent, and prevent tilting of the clips when the opening levers act to open the clips.

I will describe, with reference to the accompanying drawings, clips made in accordance with my invention.

Figures 1 and 2 are side elevations shewing parts in different positions and Figures 3 and 4, are, respectively, a front elevation and a plan of a construction in which the body part of the clips is provided with but one vertical arm. Figures 5 and 6 shew details as hereinafter explained. Figures 7 and 8 are side elevations shewing parts in different positions and Figures 9 and 10, are, respectively, a front view and a sectional plan, of a modification in which certain of the improvements are applied to a clip having two vertical arms.

Referring first to Figures 1 to 6, both 75 inclusive, the body of the clip comprises the chain link D and the vertical arms C projecting upward therefrom. The plate O of the lower jaw lies on the body of the chain link D, while the upper jaw B is pivoted to the chain link D at G by the arm B¹. The lever a of the gauge tongues A have hinges F placed on the arm B¹ of the upper jaw in a manner which will be described later. I so arrange the lever a of the gauge-tongues, A as to bring one of its arms thereof outside one of the arms B¹, of the connection of the upper jaw B with its axis in such manner that I can, when so desired, lighten the clip by dispensing with 80 one of the vertical arms, constituting, with the chain link D, the body of the clip. Pivoted on the arm B¹ of the upper jaw at center j is a unitary member comprising the opening lever J¹ and the wedging cam J. 85 On the vertical arm, C, I provide an abutment N (see the detail view Figure 5) to engage the part E of one of the arms of the lever a of the gauge-tongues A, when the said tongues are bearing on the cloth and 90

to hold the upper jaw B open until the selvedge of the cloth moves from under the gauge-tongues. The said abutment may for example, be a hinged stop, as shewn in the drawings, allowing the gauge-tongues, to rise and fall to compensate for inequalities in the thickness of the cloth fed to the stentering machine.

By arranging the said abutment N upon the arm, or upright, C, instead of upon a pin extending across the clip from one vertical arm, or upright, to another, I avoid obstruction to the opening of the upper jaw B, as widely as may be required to conveniently feed the cloth to the clips, or to clean them when required, whilst the improved arrangement of the parts gives a clear space for the spring H, (which exerts pressure on the upper jaw when closed) and allows the hinge F for the lever a of the gauge-tongues, or fingers, A, to be placed on the arm B¹ of the upper jaw at such distance from the centre G, on which the upper jaw B turns, as will, whilst giving sufficient leverage for the spring on the upper jaw through the wedging-cam J centered to it at j, prevent the said spring causing undue pressure of the gauge-tongues, A on the fabric. A stud K can be provided, below the hinge F for the lever of the gauge-tongues, to cause the said gauge-tongues, to be raised as the clip is opened.

Referring to Figure 6 it will be seen that the rod, or tube, constituting the spindle L which turns on the same centre as the upper jaw and guides the spring H, is slotted for the reception of a curved part, or mid-feather, M on the wedging-cam J, instead of the said spindle passing through a hole in the part which comprises the wedging-cam. The upper end of the spring, H bears against a shoe h, to allow of free sliding action between it and the curved under part of the mid-feather M of the cam J.

According to the modification shewn in Figures 7 to 10, both inclusive, the arms of the lever a of the gauge-tongues, A can be hinged to the vertical arm, or upright, or arms, or uprights, of the body of the clip instead of to the arm, of the upper jaw which will give a construction which is simpler than that hereinbefore described and illustrated and avoid the forward movement of the lever of the gauge-tongues, or fingers, when opening and feeding the clips.

The forward side of the snug N² on the upper jaw B engages the rear side of a snug E² on an arm of the lever a of the gauge-tongues, or fingers, A when they are resting on the cloth and, when the said gauge-tongues, or fingers, (on the cloth moving from beneath them) pass through the slots in the plate O of the lower jaw, the upper jaw B is released. A snug K² on the arm B¹ of the upper jaw B engages the under-

side of the snug E² to raise the gauge-tongues, or fingers, when the upper jaw B is opened for the cloth to be fed into the clip.

There may be a projecting snug P on the top of the vertical arm, or upright, C (or arms, or one, or both, of such uprights) of the body of the clip to bear against a plate, or the equivalent, Q, and take the thrust from the clip-openers, or cams, at each end of the machine to prevent tilting 75 of the clips.

What I claim is:—

1. In a stentering machine clip having an upper jaw provided with arms hinged to the body part of the clip, a hinged gauge tongue, arms for said gauge tongue, one of said gauge tongue arms being arranged outwards of one of the upper jaw arms, an abutment on the body part of the clip, and a projection on said outward gauge tongue arm adapted to engage said abutment when said gauge tongue is resting on the fabric; in combination with a wedging cam hinged to the upper jaw arms, a spring adapted to press said wedging cam against the body part of the clip, and means whereby the gauge tongue is raised as the upper jaw is opened; all arranged so that the pressure which is exerted by said spring upon the upper jaw does not exert objectionable pressure upon the gauge tongue as it rests upon the fabric. 95

2. In a stentering machine clip, a body part having only one vertical arm, an abutment on said arm, an upper jaw provided with arms hinged to the body part of the clip, a hinged gauge tongue, arms for said gauge tongue, one of said gauge tongue arms being arranged outwards of one of the upper jaw arms, and a projection on said outward gauge tongue arm adapted to engage said abutment on the vertical arm of the body part of the clip when said gauge tongue is resting on the fabric, in combination with a wedging cam hinged to the upper jaw arms, a spring adapted to press said wedging cam against the vertical arm of the body part of the clip, and means whereby the gauge tongue is raised as the upper jaw is opened; all arranged so that the pressure which is exerted by said spring upon the upper jaw does not exert objectionable pressure upon the gauge tongue as it rests upon the fabric. 110

3. In a stentering machine clip according to claim 1, a pivoted rod slotted at its free end on which said spring is mounted, a slider bearing against one end of said spring, and a mid feather portion of said wedging cam having a curved part lying in the slotted end of said rod and bearing upon said slider. 120

4. In a stentering machine clip according to claim 1, an opening lever on said wedging cam, a vertical arm on the body part 130

of the clip, and a protecting snug near the top of said vertical arm in combination with a stationary plate against which said snug is adapted to take to prevent tilting of the clip when said opening lever is actuated.

In testimony whereof I have signed my

name to this specification in the presence of two subscribing witnesses.

ALFRED AUSTIN WHITLEY.
